UNITED STATES PATENT OFFICE

HERMAN A. UNKE, OF CLEVELAND, OHIO

THREAD PROTECTOR

Application filed April 19, 1928. Serial No. 271,187.

This invention relates to devices for protecting the threads of pipes and other parts, during shipment and handling, and this application is in part a division of my earlier application Serial No. 131,943, filed August 27, 1926, and the invention herein described is also disclosed in my earlier application Serial No. 135,544, filed September 15, 1926.

It is one of the objects of the invention to provide an improved form of thread protector that will be very low in cost and will be adapted to be readily placed in position over the threads and not likely to become displaced while the pipe is being handled.

Other objects of the invention and the features of novelty will be apparent from the following description taken in connection with the accompanying drawings, of which—

Fig. 1 is an elevation of the end of a piece of pipe on which there is shown one form of thread protector, embodying my invention, the protector being shown in section on line 1—1 of Fig. 2;

Fig. 2 is an elevation of the left-hand end of the protector, shown in Fig. 1;

Fig. 3 is an end elevation of another form of protector embodying this invention; and

Fig. 4 is an axial section of the same.

In the form of protector illustrated in Figs. 1 and 2, I provide a cup-shaped sleeve 33, the internal diameter of which is larger than the external diameter of the threads, and this sleeve has a circumferential bead 34, at its inner end, adapted to engage between two threads. As the sleeve 33 is manufactured, the bead 34 is not of annular form, being slightly distorted as shown in Fig. 2. When the sleeve is forced over the threads, the latter tend to spring the bead 34 into annular form but the resiliency of the metal of the sleeve causes the bead to spring into the space between two threads and thereby hold the sleeve in position. The end flange 35 engages the end of the pipe, and while the bead 34 and the flange 35 do not make tight joints with the pipe, these connections are sufficiently tight to permit this form of protector to be used for protecting the threads in such coating operations as galvanizing. A slight amount of the galvanizing material

will work into the space between the threads and the protector, but experience has shown that the amount of the coating material that adheres to the threads is relatively insignificant but is sufficient to prevent rusting during the time that the pipe is normally held in storage or is in transit.

To increase the resiliency of the metal of the beaded end so that the protector will engage the threads very firmly, and to materially strengthen and thus fortify the protector against permanent distortion, I harden and stiffen the metal of that portion of the protector in which the bead 34 is located. This hardening and stiffening of the metal may be accomplished by working or stressing the metal of this portion of the protector, as by rolling, or by means of drawing dies such as are disclosed by me in said earlier application, Serial No. 135,544, filed September 15, 1926, and which I have found to be very effective.

In the protector shown in Figs. 1 and 2, the end having the bead 34 is made slightly oval in shape, and in the protector shown in Figs. 3 and 4 the end having the bead 36 is slightly flattened at a plurality of points, as shown at 37, 38 and 39. In other respects, the construction illustrated in Figs. 3 and 4 is substantially the same as that illustrated in Figs. 1 and 2.

Having thus described my invention what I claim is:

1. In combination with a threaded element, a thread protector comprising a metal sleeve having at one end thereof an end wall portion engaging the end of the threaded element, and at its other end said sleeve having a non-circular inturned annular bead engaging the threads of said element at spaced points only.

2. In combination with a threaded element, a thread protector comprising a metal sleeve having at one end thereof a wall portion engaging the end of the threaded element, and a circumferentially-extending non-circular bead at the other end engaging the threads of said element at spaced points only, the metal of said bead being substantially

harder than that at the first mentioned end of said sleeve.

3. A protector for a threaded element, comprising a metal sleeve having a laterally extending wall portion at one end thereof, and at its other end said sleeve having a radially flexible non-circular continuous bead for engagement with the threads of said element at spaced points only.

10 4. A protector for a threaded element, comprising a metal sleeve having means at one end thereof for engagement with the end of said element, and a circumferential in-turned bead at its other end, said bead having 15 spaced portions thereof lying at a shorter radial distance from the axis of said sleeve than the sections of said bead intermediate said spaced portions.

5. A protector for a threaded element, 20 comprising a metal sleeve having means at one end thereof for engagement with the end surface of said element, and non-circular means at its other end for engagement with the threads of said element at spaced points 25 only, said non-circular means comprising a substantially smooth continuous annular bead.

In testimony whereof, I hereunto affix my signature.
